UNITED STATES PATENT OFFICE.

NOAH W. BENNETT, OF QUINCY, MICHIGAN.

DESIGN FOR A TRACE-CARRIER FRAME.

SPECIFICATION forming part of Design No. 30,277, dated February 28, 1899.

Application filed February 2, 1899. Serial No. 704,294. Term of patent 14 years.

To all whom it may concern:

Be it known that I, NOAH W. BENNETT, a citizen of the United States, residing at Quincy, county of Branch, and State of Michigan, have 5 invented and produced a new and useful Design for a Trace-Carrier Frame, of which the following is a specification.

In the drawings, Figure 1 is a plan view; Fig. 2, a side elevation, and Fig. 3 an end 10 elevation; Fig. 4, a horizontal section on the line 4 4 of Fig. 2.

The device consists of two parallel bars *a*, connected at their end by arches *b*, these arches and the bars *a* forming substantially 15 a rectangular open frame, each arch consisting of a bar which rises from the ends of bars *a*. Projecting laterally from the lower ends of each of the arches *b* is an open angular

loop *e*, and connecting the two arches midway their length is a bar *f*. A slot or notch *g* is 20 formed in each of the arched bars *b* midway its length, this notch extending inward into the ends of the bar *f* a short distance. Across the mouth of each of these notches is a pivot 25 *h* to receive the usual depending tongues. (Shown in dotted lines in Fig. 3.)

I claim—

The design for a trace-carrier frame, substantially as herein shown and described.

In testimony whereof I hereunto affix my 30 signature, in the presence of two witnesses, this 14th day of December, 1898.

NOAH W. BENNETT.
